RAILWAY SIGNALING SYSTEM

Frank H. Nicholson, Penn Township, Allegheny County, and Crawford E. Staples, Pittsburgh, Pa., assignors to The Union Switch & Signal Company, Swissvale, Pa., a corporation of Pennsylvania

Application July 30, 1942, Serial No. 452,894

13 Claims. (Cl. 246—38)

Our invention relates to railway signaling systems of the type employing coded energy in the track circuits thereof.

In signaling systems of the type employing frequency code it is customary to employ energy of 75, 120 and 180 code frequency to provide three distinctive proceed indications. These are adequate for most situations, but in some cases it is desired to provide another or fourth proceed indication.

It is an object of this invention to provide improved means for producing an additional indication in a coded signaling system.

A further object of the invention is to provide apparatus arranged so that when locomotives equipped with cab signal apparatus arranged to provide three proceed indications are operated over stretches where the wayside apparatus is arranged to provide four proceed indications, the locomotive cab signal equipment will operate at all times to provide an appropriate indication.

Another object of the invention is to provide a signaling system of the type described which will not interfere with the operation of a lockout circuit if such a circuit is employed.

Other objects of the invention and features of novelty will be apparent from the following description taken in connection with the accompanying drawing.

In practicing our invention we provide means for at times modifying the energy of 75 code frequency by substantially reducing the length of every third "off" period in the code and correspondingly increasing the length of the succeeding "on" period. Means are provided to detect this special code, including a slow release detector relay to which an impulse of energy is supplied on release of the track relay contacts and which has a release period such that it remains picked up during the short "off" period but not throughout an "off" period of normal length. In addition, energy is supplied to this detector relay over a stick circuit if the relay is still picked up when the track relay contacts pick up again. When the contacts of the track relay and of the slow release detector relay are picked up, a circuit is established to supply energy to a second slow release relay which is sufficiently slow acting to remain picked up during the intervals between the short "off" periods in the modified code.

We shall describe one form of apparatus embodying our invention, and shall then point out the novel features thereof in claims.

In the drawing,

Fig. 1 is a diagram of a stretch of railroad track 55 The rails of each track section form a part of

equipped with one form of signaling apparatus embodying our invention, and

Fig. 2 is a diagram of the modified coded energy employed in the system of this invention.

5 Referring to Fig. 1 of the drawing, there is shown therein a stretch of railroad track over which traffic normally moves in the direction indicated by the arrow, that is, from left to right. The track rails 1 and 2 of the track stretch are divided by insulated joints 3 into track sections for signaling purposes.

Electric current may be employed for propulsion purposes and where this is so alternating current energy is employed in the track circuits, and impedance bonds 4 of the customary form are provided to conduct the propulsion current around each pair of insulated rail joints. As the description proceeds, however, it will be apparent that the apparatus of this invention is equally well suited for use on a steam road in which either direct or alternating current may be employed in the track circuits, while the impedance bonds may be omitted.

25 In addition, as impedance bonds are employed the signaling apparatus includes means to check the insulated joints. As here shown, this means is the non-cascading lockout circuit of United States Patent No. 2,235,134 issued March 18, 1941, to Leslie R. Allison and Frank H. Nicholson. If our present invention is employed in a track stretch where impedance bonds are not required, the portions of the signaling apparatus relating to the lockout circuit may be omitted.

35 Similarly, the decoding means provided by this invention for detecting the modified 75 code is not limited to use in wayside apparatus but may be incorporated in cab signal apparatus for use on locomotives.

In the diagram forming Fig. 1 of the drawing 40 one complete section 12T and parts of the two adjoining sections 11T and 13T, are shown. Each of these sections has located at the entrance end thereof a signal S for governing traffic in the track stretch. The signals illustrated are of the 45 familiar color light type and each signal has an upper and a lower portion each of which has a green, a yellow and a red lamp. The invention, however, is not limited to the use of signals of this type and any appropriate form of signal may be used. Likewise, the invention is not limited to a system employing wayside signals, but is 50 equally applicable to track stretches without wayside signals and having provision for cab signals only.

a track circuit to which coded alternating current signal control energy is supplied at the exit or leaving end from the secondary of a track transformer 11TT. The alternating current supplied to the track circuits is derived from a suitable source and may be distributed throughout the track stretch by a transmission line, not shown. The terminals of the power supply source are designated BX and CX, and it will be assumed that the energy supplied from this source is alternating current of a frequency of 60 cycles per second.

The signaling system shown in Fig. 1 makes use of track circuit energy coded at four different frequencies. This coded energy is provided by code transmitters CT which interrupt the supply circuits for the associated track transformers a definite number of times per minute according to traffic or other conditions ahead. As shown, each code transmitter is provided with four circuit making and breaking contacts which are continuously actuated by a motor or other suitable mechanism. The rate of operation of the contacts 75, 120 and 180 is such as to provide 75, 120 and 180 energy pulses per minute, respectively, which are separated by periods of equal duration in which no energy is supplied.

Each code transmitter has another contact designated 75M which is so operated as to produce two cycles of coded energy of 75 code frequency in which the "on" and "off" periods are of approximately equal duration, while every third code cycle is modified in such manner that the "off" period is much shorter than normal and the length of the "on" period is correspondingly increased. The pattern of this code is shown in Fig. 2. Since the distinguishing characteristic of the 75M code occurs in every third code cycle of the 75 code, the 75M code is in effect energy of 75 code frequency modulated 25 times a minute.

The details of construction of the code transmitters to cause them to produce the 75M code are not a part of this invention. However, this special coded energy may be generated by cam wheels of suitable design such as those shown in United States Patent No. 1,861,488, issued June 7, 1932 to Leslie A. Allison and Frank H. Nicholson.

Each track circuit includes a code following track relay connected across the section rails at the entrance end of the section. As shown, the relay 12TR is of the direct current type and is connected to the track rails through a resonant rectifier unit 12RU. This unit includes a transformer, a capacitor and a reactor so arranged and proportioned as to freely pass 60 cycle signal control energy but so as not to pass propulsion current of a different frequency. The unit RU includes, in addition, a rectifier which converts into direct current the alternating current supplied through the unit.

The track relay 12TR has associated therewith auxiliary relays 12FSA, 12BSA, 12HA, 12HB, 12K, 12J and 12TRB, a decoding transformer 12DT, and a timing unit 12TU, while each of the other signals in the track stretch has associated therewith equipment corresponding to that associated with signal 12S.

Each signal also has associated therewith a source of direct current, such as a storage battery, not shown, the terminals of which are designated B and C.

The equipment is shown in the condition which it assumes when the track stretch is vacant. At such times energy of 180 code frequency is supplied to the track transformer 12TT by the equipment associated with section 13T. The equipment for section 13T operates in the same manner as that for section 12T.

The coded energy supplied to track transformer 12TT feeds to the track relay 12TR and produces code following operation of this relay. As a result of operation of the relay 12TR, energy is alternately supplied to the two portions of the primary 20 of transformer 12DT from the direct current source. During the picked-up periods of the track relay contacts energy is supplied from the transformer secondary winding 22 to the pick-up winding of the relay 12FSA over the circuit established by the track relay contact 16, while during the released periods of the track relay its contact 16 establishes a snubbing circuit for the relay 12FSA to keep the contacts of the latter relay picked up during the "off" periods in the code.

When the track relay contacts are released, energy is supplied to the relay 12BSA over a circuit which includes back contact 17 of the track relay and front contact 26 of the relay 12FSA, while contact 26 also connects a snubbing resistor 28 across the terminals of the winding of relay 12BSA to make it slow in releasing.

At this time the relay 12HA is energized by current supplied over its stick circuit which is traced from terminal B through its own front contact 29, front contact 30 of relay 12BSA, winding of relay 12HA and back contact 46 of relay 12TRB to terminal C. A resistor 32 is connected across the terminals of the winding of relay 12HA to make the relay slow to release.

The relays 12K and 12J are energized from the decoding transformer through resonant units 120DU and 180DU, respectively, which include inductances and capacitances arranged and proportioned to permit energy to flow freely through the units when the frequency of the current supplied thereto is that which is present when the track relay is responding to energy of 120 and 180 code frequency, respectively, and to substantially prevent flow of energy at other times. Each of these units also includes a rectifier for rectifying the energy supplied through the unit.

As the track relay is responding to energy of 180 code frequency, energy is supplied through the unit 180DU to relay 12J and its contacts are picked up. Accordingly, contact 32 of relay 12J interrupts the circuit through which energy is supplied to the timing unit 12TU, and as a result energy is not supplied from this unit to the relay 12TRB and its contacts remain released so that the contacts of relay 12HB also remain released.

As relays 12HA and 12J are picked up, energy is supplied to the upper green lamp G of signal 12S over a circuit which includes front contact 34 of relay 12HA and front contact 35 of relay 12J, while energy is supplied to the lower red lamp R of this signal over a circuit which includes front contact 36 of relay 12HA and front contact 38 of relay 12J. Accordingly, the signal 12S displays a green over a red light which is its clear or least restrictive indication.

At this time energy of 180 code frequency is supplied to track transformer 11TT over a circuit which is traced from terminal BX through contact 180 of the code transmitter 12CT, front contact 40 of relay 12J, front contact 42 of relay 12HA, front contact 43 of relay 12BSA, front contact 44 of relay 12FSA, and the primary winding of the track transformer 11TT to terminal CX. Accordingly, energy of 180 code frequency is supplied to the rails of section 11T and the signal for

that section is caused to display its clear indication.

When a train moving in the normal direction of traffic enters section 12T, the track relay 12TR is shunted and relay 12FSA releases so that its contact 26 interrupts the supply of energy to relay 12BSA and also interrupts the snubbing circuit for this relay, with the result that relay 12BSA quickly releases. On release of relay 12BSA its contact 30 interrupts the circuit of relay 12HA, while when the track relay ceases to follow code, energy is no longer supplied to relay 12J and its contacts release.

As a result of release of the relays 12HA and 12J, the circuit of the upper green lamp G of signal 12S is interrupted, and the upper red lamp R is lighted by current supplied over back contact 34 of relay 12HA; also the circuit traced above for the lower red lamp R is interrupted and this lamp is lighted by energy supplied over back contact 36 of relay 12HA. The signal now displays a red lamp over a red lamp which is its stop or most restrictive indication.

At this time energy of 75 code frequency is supplied to the track transformer 11TT over a circuit which is traced from terminal BX through back contact 43 of relay 12BSA, back contact 44 of relay 12FSA, and contact 75 of the code transmitter 12CT.

When the train enters section 13T, the equipment for that section operates in the same manner as the equipment for section 12T so that signal 13S provides its stop indication, while energy of 75 code frequency is supplied to the track transformer 12TT.

When the train vacates section 12T, coded energy feeds to the track relay 12TR, and on the first movement of the track relay contacts to their picked-up position an impulse of energy is supplied from the secondary winding 22 of transformer 12DT to the pick-up winding of relay 12FSA.

At this time the holding winding of relay 12FSA is short circuited by back contact 21 of the relay so that the relay is slow to pick up. The relay and transformer are proportioned so that the first impulse of energy supplied to the relay will not pick up the relay contacts. However, on the next or second picked-up period of the track relay contacts the contacts of relay 12FSA pick up and contact 26 establishes the circuit of the relay 12BSA so that on the next or second released period of the track relay contacts energy is supplied to the relay 12BSA and its contacts pick up. On picking up of the track relay contacts after picking up of the contacts of relay 12BSA energy is supplied to the relay 12HA over a circuit which is traced from terminal B through front contact 17 of the track relay, front contact 20 of relay 12BSA, winding of relay 12HA, and back contact 46 of relay 12TRB to terminal C. On picking up of the contacts of relay 12HA its contact 29 establishes a circuit to maintain the relay energized as long as the relay 12BSA is picked up and the relay 12TRB is released, while contact 29 of relay 12HA interrupts the circuit for supplying energy to the holding winding of relay 12FSA.

On continued code following operation of the track relay energy is supplied to the relay 12FSA during the picked-up periods of the track relay and is supplied to the relay 12BSA during the released periods of the track relay. Accordingly, these relays are picked up and relay 12BSA maintains the circuit of the relay 12HA.

On picking up of the contacts of relay 12FSA

its contact 44 interrupts the circuit traced above for supplying energy of 75 code frequency to track transformer 11TT, and establishes a circuit including back contact 43 of relay 12BSA for supplying steady uncoded energy to section 11T.

As explained in the patent to Allison and Nicholson referred to above, if the insulated joints separating sections 11T and 12T are defective, this steady energy will feed across the joints and prevent release of the track relay 12TR so energy is not supplied to relay 12BSA with the result that relays 12BSA and 12HA remain released, while energy is supplied to the holding winding of relay 12FSA to keep its contacts picked up.

However, if the insulated joints are intact so that the steady energy does not reach the track relay 12TR, the contacts of this relay will release at the end of the "on" period and cause energy to be supplied to the relay 12BSA so that its contact 43 picks up and interrupts the supply of steady energy to track transformer 11TT. When the contacts of relay 12HA pick up, a circuit is established to supply energy of 75M frequency to track transformer 11TT. This circuit is traced from terminal BX through contact 75M of the code transmitter, back contact 48 of relay 12HB, back contact 49 of relay 12K, back contact 48 of relay 12J, front contact 42 of relay 12HA, front contact 43 of relay 12BSA, front contact 44 of relay 12FSA, and primary winding of transformer 11TT to transformer CX.

On the supply of this energy to section 11T the equipment for that section operates as herein-after explained to control the signal for that section to cause it to display its advance approach indication consisting of a yellow over a yellow lamp.

Similarly, when the train vacates section 13T the energy supplied to section 12T is changed from 75 to 75M code frequency and the relay 12HB is picked up as hereinafter explained in detail and causes the signal 12S to display its advance approach indication.

The construction of the timing unit 12TU is not a part of our invention, but is shown and claimed in application Serial No. 452,902 of Carl Volz, filed July 30, 1942. This unit includes a transformer having a primary winding which is energized in multiple with a condenser, while the secondary winding of the transformer is connected through a rectifier to the winding of relay 12TRB. The various parts of the unit are proportioned so that the energy supplied to the transformer primary winding causes the transformer core to be saturated, while on interruption of the supply of energy to the transformer primary winding, this winding and the condenser associated therewith form a highly damped oscillating circuit. The energy circulating in the transformer primary winding causes energy to be induced in the transformer secondary winding from which it is supplied through the rectifier to the relay 12TRB. The characteristics of the timing unit and of the relay 12TRB are such that on interruption of the supply of energy to the timing unit, energy is supplied therefrom to the relay 12TRB which is effective to cause the contacts of relay 12TRB to pick up and to remain picked up for a time longer than the short "off" period in the 75M code but not as long as the "off" periods in the 75 code.

When the track relay 12TR is responding to energy of 75 code frequency, energy is supplied to the primary winding of the transformer of the timing unit 12TU over the circuit which is traced

from terminal B of the source through front contact 15 of the track relay 12TR, asymmetric unit 51, front contact 52 of relay 12BSA, back contact 32 of relay 12J, back contact 53 of relay 12K, back contact 54 of relay 12TRB, and primary winding of the timing unit transformer to terminal C.

On movement of the track relay contacts to their released positions the supply of energy to the timing unit transformer is interrupted and this unit operates as explained above to supply energy through the rectifier incorporated in the unit to the relay 12TRB over the circuit which is traced from the positive output terminal of the rectifier over back contact 56 of track relay 12TR, and winding of relay 12TRB to terminal C, it being noted that the other output terminal of the rectifier is connected to terminal C. The energy supplied to the winding of relay 12TRB causes the contacts of this relay to pick up and to remain picked up for a short time interval. However, as explained above, this time interval is shorter than the "off" periods in the 75 code so that when the track relay is responding to energy of 75 code frequency the contacts of relay 12TRB release before the track relay contacts pick up again, and as a result contact 54 of relay 12TRB establishes the circuit for supplying energy to the unit 12TU on subsequent picking up of the track relay contacts. In addition, contact 58 of relay 12TRB is released and interrupts the circuit of relay 12HB so that this relay remains released at this time, and its contact 60 maintains the circuit of the lower red lamp R of signal 12S, while its contact 48 maintains the circuit for supplying energy of 75M code frequency to section 11T.

On picking up of relay 12TRB its contact 46 interrupts the circuit of relay 12HA, but this relay is sufficiently slow in releasing to remain picked up during the picked-up periods of contact 46.

As the circuit of relay 12HA includes a back contact 46 of relay 12TRB, the relay 12HA will be released if the contacts of relay 12TRB remain picked up for any reason. This arrangement checks the relay 12TRB to insure that it releases, and, therefore, permits the use of a relay having metal to metal contacts for this purpose.

When the train advances far enough to vacate section 13T, energy of 75 code frequency feeds to the track relay for that section so that signal 13S displays its approach indication, while energy of 75M code frequency is supplied to section 12T. On the supply of this energy to the track relay 12TR it continues to follow code in such manner that the relays 12FSA, 12BSA and 12HA are maintained energized. As explained above, each time the track relay contacts release the contacts of relay 12TRB pick up, while when a short "off" period in the 75M code is encountered, the contacts of the track relay pick up before the contacts of relay 12TRB release. When this occurs, energy is supplied to relay 12TRB over a circuit which is traced from terminal B through front contact 15 of track relay 12TR, asymmetric unit 51, front contact 52 of relay 12BSA, back contact 32 of relay 12J, back contact 53 of relay 12K, front contact 54 of relay 12TRB, and winding of relay 12TRB to terminal C. This energy keeps the contacts of relay 12TRB picked up throughout the long "on" period in the 75M code following the short "off" period.

In addition, on picking up of the track relay 75

contacts while the contacts of relay 12TRB are still picked up, the relays 12HB and 12BSA are energized in series over a circuit which is traced from terminal B through front contact 15 of relay 12TR, asymmetric unit 51, front contact 52 of relay 12BSA, back contact 32 of relay 12J, back contact 53 of relay 12K, front contact 54 of relay 12TRB, front contact 56 of relay 12TR, winding of relay 12HB, front contact 53 of relay 12TRB, front contact 26 of relay 12FSA, and winding of relay 12BSA to terminal C. The energy supplied to the relay 12BSA over this circuit insures that the contacts of relay 12BSA will remain picked up throughout the long "on" period in the 75M code, while the energy supplied to the relay 12HB at this time causes the relay contacts to pick up. The relay 12HB is of a type the contacts of which are slow in releasing and when the relay is energized throughout the long "on" period in the 75M code, the flux in the relay core is built up to a value such that the relay contacts will remain picked up during the intervals between the long "on" periods in the 75M code.

On picking up of the contacts of relay 12HB its contact 48 interrupts the circuit traced above for supplying energy of 75M code frequency to track transformer 11TT, and establishes a circuit for supplying energy of 120 code frequency thereto. This circuit is traced from terminal BX through contact 126 of the code transmitter, front contact 48 of relay 12HB, back contact 49 of relay 12K, back contact 40 of relay 12J, front contact 42 of relay 12HA, front contact 43 of relay 12BSA, front contact 44 of relay 12FSA, and primary winding of the track transformer 11TT to terminal CX.

When relay 12HB picks up, its contact 60 interrupts the previously traced circuit for supplying energy to the lower red lamp R of signal 12S and establishes a circuit for supplying energy to the lower yellow lamp Y of this signal. This circuit is traced from terminal B through front contact 36 of relay 12HA, back contact 38 of relay 12J, back contact 61 of relay 12K, front contact 60 of relay 12HB, and lamp Y to terminal C. Accordingly, the signal 12S displays its advance approach indication consisting of a yellow lamp over a yellow lamp.

On release of the track relay 12TR after the long "on" period in the 75M code its contact 16 interrupts the supply of energy to the relays 12TRB, 12HB, and 12BSA and the relay 12TRB releases. The contacts of relay 12HB are maintained picked up because of the slow releasing characteristic of the relay, while on release of the track relay 12TR its contact 17 establishes the previously traced circuit for supplying energy to the relay 12BSA so its contacts remain picked up.

In addition, on release of relay 12TR its contact 56 interrupts the previously traced circuit for energizing the relays 12HB and 12BSA in series and establishes the circuit to permit energy to be supplied from the timing unit 12TU to the relay 12TRB. However, during the previously picked-up period of the track relay the contact 54 of relay 12TRB interrupted the circuit for supplying energy to the primary winding of the transformer incorporated in the timing unit 12TU so that no flux is present in the transformer core, and on release of the track relay contacts there is no change in energization of the transformer primary winding. Accordingly, no energy is available from this unit and no energy is supplied to the relay 12TRB over the circuit established by back contact 56 of the track relay 12TR.

and the contacts of relay 12TRB remain released.

On the first picked-up period of the track relay contacts after the long "on" period in the 75M code energy is supplied to the primary winding of the transformer incorporated in the timing unit 12TU over the circuit including back contact 54 of relay 12TRB so that on the next released period of the track relay contacts the timing unit 12TU operates as explained above to supply energy to the relay 12TRB and its contacts become picked up. However, the "off" period in the 75M code at this time is longer than the release period of the contacts of relay 12TRB so that its contacts release before the track relay contacts pick up again. Accordingly, energy is not supplied to the relay 12HB at this time.

On the next or second picked-up period of the track relay contacts subsequent to the long "on" period energy is again supplied to the timing unit 12TU, while on the next released period of the track relay contacts, which occurs during a short "off" period in the 75M code, energy is again supplied from the timing unit 12TU to the relay 12TRB and its contacts pick up with the result that on picking up of the track relay contacts the contacts of relay 12TRB are still picked up so that energy is supplied over the holding circuit for relay 12TRB, and is also supplied to the relays 12HB and 12BSA in series.

It will be seen, therefore, that when the track relay is responding to energy of 75M code frequency and the short "off" period in the code is encountered, the track relay contacts pick up before the contacts of relay 12TRB release, and as a result energy is supplied to relay 12TRB to maintain its contacts picked up during the long "on" period which follows the short "off" period. In addition, energy is supplied to the relay 12HB to pick up its contacts and to maintain them picked up during the time intervals between the long "on" periods in the code, while energy is supplied to the relay 12BSA to maintain its contacts picked up during the long "on" period in this code. Accordingly, as long as the track relay 12TR responds to energy of 75M code frequency the contacts of relay 12HB are maintained picked up.

When the train advances far enough to vacate the section in advance of section 13T, energy of 75M code frequency is supplied to section 13T and the equipment for that section operates as explained above in connection with section 12T to cause energy of 120 code frequency to be supplied to the rails of section 12T. When the track relay 12TR responds to this energy, the frequency of the current induced in the secondary winding 23 of decoding transformer 12DT is such that it is freely passed by resonant unit 120DU and the relay 12K picks up so that contact 53 interrupts the circuit for supplying energy to the timing unit 12TU, and for supplying energy to relay 12TRB and to relays 12HB and 12BSA in series. Accordingly, relays 12TRB and 12HB thereafter remain released.

On picking up of the relay 12K its contact 61 interrupts the circuit traced above for supplying energy to the lower yellow lamp Y of signal 12S and establishes a circuit including front contact 36 of relay 12HA, back contact 38 of relay 12J, and front contact 61 of relay 12K for supplying energy to the lower green lamp G of signal 12S. The signal 12S, therefore, displays its approach medium indication consisting of a yellow lamp over a green lamp.

When the relay 12K picks up, its contact 49 interrupts the circuit traced above for supplying energy of 120 code frequency to transformer 11TT and establishes a circuit for supplying energy of 180 code frequency thereto. This circuit is traced from terminal BX through contact 180 of the code transmitter 12CT, front contact 49 of relay 12K, back contact 40 of relay 12J, and front contacts of the relays 12HA, 12BSA and 12FSA to the transformer 11TT.

When the train advances far enough to vacate two sections in advance of section 13T, energy of 120 code frequency is supplied thereto and the equipment for that section operates to supply energy of 180 code frequency to track transformer 12TT. When this energy feeds to the track relay 12TR, the frequency of the energy induced in transformer secondary winding 23 is such that it is no longer passed by the resonant unit 120DU, but is freely passed by the unit 180DU so that relay 12K releases and relay 12J picks up. On picking up of relay 12J its contact 32 interrupts the circuit of the timing unit 12TU, and of the relays 12TRB, 12HB, and 12BSA, while its contacts 38 interrupts the circuit traced above for supplying energy to the lower green lamp G and establishes the circuit including front contact 36 of relay 12HA for supplying energy to the lower red lamp R of signal 12S. In addition, at this time contact 35 of relay 12J interrupts the circuit of the upper yellow lamp Y of signal 12S and establishes the circuit including front contact 34 of relay 12HA for supplying energy to the upper green lamp G of signal 12S. Accordingly, the signal 12S displays its clear indication consisting of a green lamp over a red lamp.

On picking up of relay 12J contact 49 interrupts the previously traced circuit for supplying energy of 180 code frequency to transformer 11TT and establishes another circuit for supplying energy of this code frequency to the transformer 11TT.

From the foregoing it will be seen that the system of this invention operates to provide four distinct proceed indications. Three of these indications are provided by the usual coded energy of 75, 120 and 180 code frequencies, while one of these indications is provided by the special 75M code which is a modification of the standard 75 code.

It has been found that when locomotives equipped with cab signal apparatus of standard construction and having decoding means for detecting energy of 75, 120 and 180 code frequency are operated in sections supplied with the special 75M code, the cab signal apparatus gives the same response to the 75M code as it gives when supplied with energy of 75 code frequency. Accordingly, when a locomotive equipped with standard four indication cab signal apparatus is operated in a track stretch equipped with the five indication apparatus provided by this invention, the cab signal equipment will provide its approach indication through the two blocks in the rear of an occupied block. In such situations the wayside signal at the entrance to the second section in the rear of an occupied block will display its advance approach indication, while when the locomotive enters this section, the cab signal will provide its approach indication.

If desired, the locomotive cab signal apparatus may include means for detecting the special 75M code, and if this is done, the cab signal will provide its advance approach indication when the

locomotive is in a section to which energy of 75M code frequency is supplied.

Operation of equipment when an insulated joint is defective

The incorporation in this system of the decoding means for the energy of 75M code frequency does not substantially alter operation of the equipment to establish the "lockout" circuit if the insulated joints separating two sections are defective.

If a train breaks down one of the insulated joints separating sections 11T and 12T, energy of 75 code frequency supplied to transformer 11TT may pick up the track relay 12TR when the train advances far enough for the rear of the train to be located some distance in advance of the track relay.

On initial movement of the track relay contacts to their picked-up positions an impulse of energy is supplied through the decoding transformer 12DT to the pick-up winding of relay 12FSA, but the contacts of this relay remain released and maintain the supply of energy of 75 code frequency to the transformer 11TT, while they interrupt the circuit of relay 12BSA. At this time contact 52 of relay 12BSA is released and prevents the supply of energy through the asymmetric unit 51 to the timing unit 12TU. As relay 12FSA remains released energy is not supplied to the relay 12BSA on release of the track relay.

On the next or second movement of the track relay contacts to their picked-up positions another impulse of energy is supplied to the pick-up winding of relay 12FSA and its contacts pick up with the result that contact 44 interrupts the circuit for supplying energy of 75 code frequency to the transformer 11TT and establishes the circuit including back contact 43 of relay 12BSA for supplying steady uncoded energy to the transformer 11TT. This energy feeds across the defective joints and keeps the track relay contacts picked up.

As the track relay contacts and the contacts of relay 12FSA are picked up, energy is supplied to the holding winding of relay 12FSA over the circuit which is traced from terminal B through front contact 17 of the track relay, back contact 29 of relay 12HA, front contact 27 of relay 12FSA, and holding winding of the relay 12FSA to terminal C. The energy supplied to the holding winding of relay 12FSA keeps the relay contacts picked up so that its contact 27 maintains the circuit of the relay holding winding, while its contact 44 maintains the circuit for supplying steady energy to the transformer 11TT. This energy feeds across the defective joints and keeps the track relay contacts picked up with the result that energy is not supplied to the relay 12BSA and its contacts remain released and interrupt the circuit of relay 12HA so that relay 12HA remains released and causes signal 12S to continue to display its stop indication.

If an insulated joint separating sections 11T and 12T breaks down when section 12T is vacant, the coded energy feeding from transformer 11TT across the defective joint to track relay 12TR combines with energy supplied from transformer 12TT to the track relay 12TR. If at the time the insulated joint becomes defective the impulses of coded energy supplied to transformers 11TT and 12TT are out of step, the contacts of track relay 12TR will be held picked up an abnormally large proportion of the time. If at the time the insulated joint becomes defective the impulses of

coded energy supplied to the transformers 11TT and 12TT are in step, they will soon become out of step as the code transmitters controlling the supply of energy to the two sections are operated by induction motors and these will not run at exactly the same speed for any substantial period of time.

As a result of the increase in the picked-up periods of the track relay contacts, the circuit of the relay 12BSA is interrupted so much of the time that this relay will release with the result that its contact 43 interrupts the circuit for supplying coded energy to the transformer 11TT and establishes a circuit to supply steady energy thereto. This energy feeds across the defective joint and keeps the track relay contacts picked up so that energy is no longer supplied through the decoding transformer 12DT to the relay 12FSA, nor to the relay 12K or 12J, so that these relays release.

In addition, on release of relay 12BSA its contact 30 interrupts the circuit of relay 12HA and the contacts of this relay release, but because of the slow releasing characteristic of this relay its contact 29 remains picked up and interrupts the circuit for supplying energy to the holding winding of relay 12FSA until after contact 27 of relay 12FSA has released and interrupted this circuit.

On release of relay 12BSA its contact 52 interrupts the circuit for supplying energy to the timing unit 12TU, and also to relays 12TRB, 12HB and 12BSA.

On release of relay 12FSA its contact 44 interrupts the supply of steady energy to transformer 11TT and causes energy of 75 code frequency to be supplied thereto over the circuit which is traced from terminal BX through back contact 43 of relay 12BSA, back contact 44 of relay 12FSA, and contact 75 of the code transmitter 12CT to the transformer 11TT. Energy from the transformer feeds across the defective joint to track relay 12TR and combines with the energy supplied from transformer 12TT.

The impulses of coded energy supplied to the track relay 12TR from the transformers 11TT and 12TT will cause the contacts of the track relay to be picked up most of the time, but a time will soon be reached when the relationship of the two codes is such that the track relay contacts will pick up twice in rapid succession. When this occurs, the relay 12FSA will pick up and its contact 27 will establish the circuit traced above for supplying energy to the relay holding winding so that the relay contacts are thereafter maintained picked up. In addition, on picking up of the relay 12FSA its contact 44 interrupts the circuit for supplying energy of 75 code frequency to transformer 11TT and establishes the circuit for supplying steady energy thereto. This energy keeps the track relay 12TR picked up so that energy is not supplied to relay 12BSA. Accordingly, the contacts of relay 12BSA remain released and maintain the circuit for supplying steady energy to the transformer 11TT, and interrupt the circuit of relay 12HA so that this relay remains released and causes signal 12S to display its stop indication.

From the foregoing it will be seen that this system provides means to modify signaling systems of the frequency code type to secure an additional proceed indication, and that this additional indication is secured by modifying the energy of one code frequency in a manner which does not interfere with the operation of existing

decoding means, and if a locomotive equipped with existing cab signal apparatus is operated in a section to which the modified coded energy is supplied the locomotive cab signal apparatus will operate to provide a suitable proceed indication.

Furthermore, it has been found that energy of the code pattern employed for the 75M code frequency has a minimum effect on the decoding units for energy of 120 and 180 code frequency.

It will be seen also that the decoding means for detecting the energy of 75 code frequency is arranged so that it does not interfere with the lockout circuit. The relay BSA has a release time just long enough to bridge the picked-up periods of the track relay when the track relay is supplied with energy of 75 code frequency so that this relay will release quickly and establish the lockout circuit if energy feeds across a defective joint and keeps the track relay picked up an abnormally large proportion of the time. The decoding means for the 75M code frequency includes means for supplying energy to the relay ESA during the long "on" periods in this code to thereby prevent release of this relay at such times and resultant interference with the supply of energy to the adjacent section in the rear. This means for supplying energy to the relay BSA is effective only during the long "on" periods in the 75M code so that there is a minimum of interference with the release of the relay BSA.

In addition, the 75M decoding means is controlled by the relays which detect the other code frequencies so that the 75M decoding means is prevented from functioning if the relays which detect energy of 120 and 180 code frequency are picked up. This reduces the period of operation of the 75M decoding means, while it prevents operation of this means in response to momentary release of the track relay contacts occurring when the track relay starts to follow code, when there is a change in the frequency of the energy supplied to the track relay, or when the track relay is supplied with energy of 120 or 180 code frequency.

Similarly, the decoding means for the 75M code is controlled by the relay BSA so that this decoding means will function only when the track relay is responding to coded energy.

The modified code employed in this system and the decoding means for this code are of such nature that coded energy resulting from modifications of the standard code due to track circuit or other conditions will not operate this decoding means. The short "off" period in the 75M code must be present to cause the contacts of the track relay and of the relay TRB to both be picked up at the same time to establish the circuit to supply energy to the relay HB. Furthermore, energy is supplied to the relay HB only during every third code cycle, and energy must be supplied to this relay for a considerable period in order to keep the contacts of the relay picked up during the comparatively long intervals in which energy is not supplied to the relay.

In the modified code employed in this system the short "off" period is followed by a long "on" period and energy is supplied to the relay HB throughout this long "on" period so that enough energy is supplied to the relay to keep it picked up during the interval between the long "on" periods. These long "on" periods are substantially longer than the "on" periods present in any of the standard codes and will not be produced by modifications of those codes by track circuit conditions.

In addition, the special code employed in this system is arranged so that the modified code cycles are of the same length as the code cycles of standard pattern, and the code can be generated by existing types of motor driven code transmitters with only a slight modification thereof consisting of the addition of another cam.

Although we have herein shown and described only one form of apparatus embodying our invention, it is understood that various changes and modifications may be made therein within the scope of the appended claims without departing from the spirit and scope of our invention.

Having thus described our invention, what we claim is:

1. In a coded signaling system, in combination, a code following relay, means for at times supplying to said relay recurring cycles of coded energy, each of said cycles consisting of two periods of substantially equal length, one of said periods being an "on" period during which energy is supplied to said relay and the other of said periods being an "off" period during which no energy is supplied, means for at times periodically modifying the cycles of coded energy supplied to said relay by substantially reducing the length of a predetermined one of the periods of said code cycle, a first relay responsive to operation of said code following relay by either normal or modified coded energy, an auxiliary relay, means operative on response of said code following relay to said predetermined code periods to supply to said auxiliary relay energy effective to pick up the contacts of said auxiliary relay and to maintain them picked up for a time longer than a period of reduced length but not as long as a period of normal length, a circuit including a front contact of said auxiliary relay and a contact of said code following relay closed on response of said relay to said other code periods for supplying energy to a second relay, and signaling means governed by said first and second relays.

2. In a coded signaling system, in combination, a code following relay, means for at times supplying to said relay recurring cycles of coded energy, each of said cycles consisting of two periods of substantially equal length, one of said periods being an "on" period during which energy is supplied to said relay and the other of said periods being an "off" period during which no energy is supplied, means for at times periodically modifying the cycles of coded energy supplied to said relay by substantially reducing the length of a predetermined one of the periods of said code cycle, a first relay responsive to operation of said code following relay by either normal or modified coded energy, an auxiliary relay, means operative on response of said code following relay to said predetermined code periods to supply to said auxiliary relay energy effective to pick up the contacts of said auxiliary relay and to maintain them picked up for a time longer than a period of reduced length but not as long as a period of normal length, a circuit including a front contact of said auxiliary relay and a contact of said code following relay closed on response of said relay to said other code periods for also supplying energy to said auxiliary relay, and signaling means governed by said code following relay and said auxiliary relay and by said first relay.

3. In a coded signaling system, in combination, a code following relay, means for at times supplying to said relay recurring cycles of coded

energy, each of said cycles consisting of two periods of substantially equal length, one of said periods being an "on" period during which energy is supplied to said relay and the other of said periods being an "off" period during which no energy is supplied, means for at times periodically modifying the cycles of coded energy supplied to said relay by substantially reducing the length of a predetermined one of the periods of said code cycle, a first relay responsive to operation of said code following relay by either normal or modified coded energy, an auxiliary relay, means operative on response of said code following relay to said predetermined code periods to supply to said auxiliary relay energy effective to pick up the contacts of said auxiliary relay and to maintain them picked up for a time longer than a period of reduced length but not as long as a period of normal length, a slow releasing relay, a circuit including a front contact of said auxiliary relay and a contact of said code following relay closed on response of said relay to said other code periods for supplying energy to said slow releasing relay and for also supplying energy to said auxiliary relay, and signaling means governed by said first relay and by said slow releasing relay.

4. In a coded signaling system, in combination, a code following relay, means for at times supplying to said relay recurring cycles of coded energy, each of said cycles consisting of two periods of substantially equal length, one of said periods being an "on" period during which energy is supplied to said relay and the other of said periods being an "off" period during which no energy is supplied, means for at times periodically modifying the cycles of coded energy supplied to said relay by substantially reducing the length of a predetermined one of the periods of said code cycle and correspondingly increasing the length of the other period of said code cycle, a first relay responsive to operation of said code following relay by either normal or modified coded energy, an auxiliary relay, means operative on response of said code following relay to said predetermined code periods to supply to said auxiliary relay energy effective to pick up the contacts of said auxiliary relay and to maintain them picked up for a time longer than a period of reduced length but not as long as a period of normal length, a circuit including a front contact of said auxiliary relay and a contact of said code following relay closed on response of said relay to said other code periods for supplying energy to a second relay, and signaling means governed by said first and second relays.

5. In a coded signaling system, in combination, a code following relay, means for at times supplying to said relay recurring cycles of coded energy, each of said cycles consisting of two periods of substantially equal length, one of said periods being an "on" period during which energy is supplied to said relay and the other of said periods being an "off" period during which no energy is supplied, means for at times periodically modifying the cycles of coded energy supplied to said relay by substantially reducing the length of a predetermined one of the periods of said code cycle and correspondingly increasing the length of the other period of said code cycle, a first relay responsive to operation of said code following relay by either normal or modified coded energy, an auxiliary relay, means operative on response of said code following relay to said predetermined code periods to supply to said

auxiliary relay energy effective to pick up the contacts of said auxiliary relay and to maintain them picked up for a time longer than a period of reduced length but not as long as a period of normal length, a circuit including a front contact of said auxiliary relay and a contact of said code following relay closed on response of said relay to said other code periods for also supplying energy to said auxiliary relay, and signaling means governed by said code following relay and said auxiliary relay and by said first relay.

6. In a coded signaling system, in combination, a code following relay, means for at times supplying to said relay recurring cycles of coded energy, each of said cycles consisting of two periods of substantially equal length, one of said periods being an "on" period during which energy is supplied to said relay and the other of said periods being an "off" period during which no energy is supplied, means for at times periodically modifying the cycles of coded energy supplied to said relay by substantially reducing the length of a predetermined one of the periods of said code cycle and correspondingly increasing the length of the other period of said code cycle, a first relay responsive to operation of said code following relay by either normal or modified coded energy, an auxiliary relay, means operative on response of said code following relay to said predetermined code periods to supply to said auxiliary relay energy effective to pick up the contacts of said auxiliary relay and to maintain them picked up for a time longer than a period of reduced length but not as long as a period of normal length, a slow releasing relay, a circuit including a front contact of said auxiliary relay and a contact of said code following relay closed on response of said relay to said other code periods for supplying energy to said slow releasing relay and for also supplying energy to said auxiliary relay, and signaling means governed by said first relay and by said slow releasing relay.

7. In a coded signaling system, in combination, a code following relay, means for at times supplying to said relay recurring cycles of coded energy, each of said cycles consisting of two periods of substantially equal length, one of said periods being an "on" period during which energy is supplied to said relay and the other of said periods being an "off" period during which no energy is supplied, means for at times periodically modifying the cycles of coded energy supplied to said relay by substantially reducing the length of a predetermined one of the periods of said code cycle and correspondingly increasing the length of the other period of said code cycle, a first relay responsive to operation of said code following relay by either normal or modified coded energy, an auxiliary relay, means operative on response of said code following relay to said predetermined code periods to supply to said auxiliary relay energy effective to pick up the contacts of said auxiliary relay and to maintain them picked up for a time longer than a period of reduced length but not as long as a period of normal length, a slow releasing relay, a circuit including a front contact of said auxiliary relay and a contact of said code following relay closed on response of said relay to said other code periods for supplying energy to said slow releasing relay and for also supplying energy to said auxiliary relay, and signaling means governed by said first relay and by said slow releasing relay.

8. In a coded signaling system, in combination, a code following relay, means for supplying to said relay coded energy consisting of alternate

"on" and "off" periods of substantially equal duration, means for at times periodically modifying the coded energy supplied to said relay by substantially reducing the length of an "off" period and correspondingly increasing the length of the succeeding "on" period, a first relay responsive to operation of said code following relay by either normal or modified coded energy, an auxiliary relay, means operative on release of the contacts of said code following relay to supply to said auxiliary relay energy effective to pick up the contacts of said auxiliary relay and to maintain them picked up for a time longer than an "off" period of reduced length but shorter than an "off" period of normal length, a circuit including front contacts of said code following relay and of said auxiliary relay for supplying energy to said auxiliary relay, a second relay governed by said code following relay and said auxiliary relay, and signaling means controlled by said first and second relays.

9. In a coded signaling system, in combination, a code following relay, means for supplying to said relay coded energy consisting of alternate "on" and "off" periods of substantially equal duration, means for at times periodically modifying the coded energy supplied to said relay by substantially reducing the length of an "off" period and correspondingly increasing the length of the succeeding "on" period, a first relay responsive to operation of said code following relay by either normal or modified coded energy, an auxiliary relay, means operative on release of the contacts of said code following relay to supply to said auxiliary relay energy effective to pick up the contacts of said auxiliary relay and to maintain them picked up for a time longer than an "off" period of reduced length but shorter than an "off" period of normal length, a circuit including front contacts of said code following relay and of said auxiliary relay for supplying energy to said auxiliary relay, a slow releasing relay, a circuit including front contacts of said code following relay and of said auxiliary relay for supplying energy to said slow releasing relay, and signaling means governed by said first relay and by said slow releasing relay.

10. In a coded railway signaling system, in combination, a stretch of railway track over which traffic normally moves in one direction, the rails of said section being divided by insulated joints into a forward and a rearward section, a code following track relay at the entrance end of the forward section and having a winding receiving energy over the rails of said section, means at the exit end of said forward section for supplying to the rails of said section coded energy consisting of alternate "on" and "off" periods of substantially equal duration, means for at times periodically modifying the coded energy supplied to said section by substantially reducing the length of an "off" period and correspondingly increasing the length of the succeeding "on" period, means including a front contact of said track relay for supplying energy to a first auxiliary relay, means including a back contact of the track relay and a front contact of said first auxiliary relay for supplying energy to a second auxiliary relay, said second auxiliary relay being slow enough in releasing to remain picked up for a period approximately as long as an "on" period of normal length after the supply of energy thereto is interrupted, means for supplying coded energy to the rails of said rearward section, a circuit complete when

the contacts of the first auxiliary relay are picked up and the contacts of the second auxiliary relay are released and over which steady energy may be supplied to the rails of said rearward section, 5 means operative on release of the contacts of the track relay to supply to a third auxiliary relay energy effective to pick up the contacts of said relay and to maintain them picked up for a time longer than an "off" period of reduced length but shorter than an "off" period of normal length, a circuit including front contacts of said track relay and of said third auxiliary relay for also supplying energy to said third auxiliary relay, a circuit including front contacts of said track relay and said third auxiliary relay for supplying energy to said second auxiliary relay, and means governed by said third auxiliary relay for supplying coded energy to the rails of said rearward section.

10 20 25 30 35 40 45 50 55 60 65 70 75 11. In a coded railway signaling system, in combination, a stretch of railway track over which traffic normally moves in one direction, the rails of said section being divided by insulated joints into a forward and a rearward section, a code following track relay at the entrance end of the forward section and having a winding receiving energy over the rails of said section, means at the exit end of said forward section for supplying to the rails of said section coded energy consisting of alternate "on" and "off" periods of substantially equal duration, means for at times periodically modifying the coded energy supplied to said section by substantially reducing the length of an "off" period and correspondingly increasing the length of the succeeding "on" period, means including a front contact of said track relay for supplying energy to a first auxiliary relay, means including a back contact of the track relay and a front contact of said first auxiliary relay for supplying energy to a second auxiliary relay, said second auxiliary relay being slow enough in releasing to remain picked up for a period approximately as long as an "on" period of normal length after the supply of energy thereto is interrupted, means for supplying coded energy to the rails of said rearward section, a circuit complete when the contacts of the first auxiliary relay are picked up and the contacts of the second auxiliary relay are released and over which steady energy may be supplied to the rails of said rearward section, means operative on release of the contacts of the track relay to supply to a third auxiliary relay energy effective to pick up the contacts of said relay and to maintain them picked up for a time longer than an "off" period of reduced length but shorter than an "off" period of normal length, means effective when the contacts of said track relay and said third auxiliary relay are picked up to supply energy to said third auxiliary relay, to said second auxiliary relay, and to a slow releasing relay, and means governed by said slow releasing relay for supplying coded energy to the rails of said rearward section.

12. In a coded railway signaling system, in combination, a stretch of railway track over which traffic normally moves in one direction, the rails of said section being divided by insulated joints into a forward and a rearward section, a code following track relay at the entrance end of the forward section and having a winding receiving energy over the rails of said section, means at the exit end of said forward section for supplying to the rails of said section coded energy consisting of alternate "on" and "off"

periods of substantially equal duration, means for at times periodically modifying the coded energy supplied to said section by substantially reducing the length of an "off" period and correspondingly increasing the length of the succeeding "on" period, means including a front contact of said track relay for supplying energy to a first auxiliary relay, means including a back contact of the track relay and a front contact of said first auxiliary relay for supplying energy to a second auxiliary relay, said second auxiliary relay being slow enough in releasing to remain picked up for a period approximately as long as an "on" period of normal length after the supply of energy thereto is interrupted, means for supplying coded energy to the rails of said rearward section, a circuit complete when the contacts of the first auxiliary relay are picked up and the contacts of the second auxiliary relay are released and over which steady energy may be supplied to the rails of said rearward section, means operative on release of the contacts of the track relay to supply to a third auxiliary relay energy effective to pick up the contacts of said relay and to maintain them picked up for a time longer than an "off" period of reduced length but shorter than an "off" period of normal length, means effective when the contacts of the track relay and of the third auxiliary relay are picked up to supply energy to said third auxiliary relay and to a slow releasing relay, means effective when the contacts of the track relay and of said third auxiliary relay are picked up to prolong the picked-up periods of the contacts of the second auxiliary relay, and means governed by said slow releasing relay for supplying energy to the rails of said rearward section.

13. In a coded railway signaling system, in combination, a stretch of railway track over which traffic normally moves in one direction, the rails of said section being divided by insulated joints into a forward and a rearward section, a code following track relay at the entrance end

of the forward section and having a winding receiving energy over the rails of said section, means at the exit end of said forward section for supplying to the rails of said section coded energy consisting of alternate "on" and "off" periods of substantially equal duration, means for at times periodically modifying the coded energy supplied to said section by substantially reducing the length of an "off" period and correspondingly increasing the length of the succeeding "on" period, means including a front contact of said track relay for supplying energy to a first auxiliary relay, means including a back contact of the track relay and a front contact of said first auxiliary relay for supplying energy to a second auxiliary relay, said second auxiliary relay being slow enough in releasing to remain picked up for a period approximately as long as an "on" period of normal length after the supply of energy thereto is interrupted, means for supplying coded energy to the rails of said rearward section, a circuit complete when the contacts of the first auxiliary relay are picked up and the contacts of the second auxiliary relay are released and over which steady energy may be supplied to the rails of said rearward section, means operative on release of the contacts of the track relay provided the contacts of the second auxiliary relay are picked up to supply to a third auxiliary relay energy effective to pick up the contacts of said relay and to maintain them picked up for a time longer than an "off" period of reduced length but shorter than an "off" period of normal length, means effective when the contacts of the track relay and of said second and third auxiliary relays are picked up to supply energy to said third auxiliary relay and to a slow releasing relay, and means governed by said slow releasing relay for supplying coded energy to said rearward section.
